Patented Apr. 19, 1960

187,722

COMBINED RADIATOR COVER, PLANTER, AND SHELVES

Augustus H. Cooper, Overbrook Hills, Pa.

Application June 25, 1957, Serial No. 46,724

Term of patent 14 years

(Cl. D81—21)

Fig. 1.

Fig. 2.

Fig. 3.

Fig. 4.

Fig. 1 is a front view of a combined radiator cover, planter, and shelves embodying my new design.

Fig. 2 is a top plan view of the combined radiator cover, planter, and shelves shown in Fig. 1.

Fig. 3 is a side view thereof.

Fig. 4 is a rear perspective view thereof.

The dominant features of the design reside in the portions shown in full lines.

I claim:

The ornamental design for a combined radiator cover, planter, and shelves, substantially as shown and described.
